23 Claims. (Cl. 155—140)

1

Our invention relates to chairs of the regular or wheel type which are designed to fold by the gathering of their sides. Chairs of this type often employ crossed diagonal braces on the inside, the folding of the braces accomplishing the gathering of the sides to the extent that these and the braces become compactly grouped. Chairs constituted as just mentioned do not provide for adjustments between the folded and open positions, and it is one of our objects to provide such adjustments, so that the width of the chair may be changed and set as desired.

Another characteristic of chairs having cross-pivoted diagonal braces is the raising of a vital portion of the chair—such as the seat support—to take up the increased height of the braces as they fold together, and a further object of the present invention is to provide means to keep the over-all height of the braces constant at all points in their range of adjustment, so that no raising or leeway need be provided for in the body of framework of the chair for changes in the height of the braces.

Another object of the invention is to limit the height of the basic chair—whether open or folded—to the approximate level of its seat, and no higher than the wheels in case the chair is of the wheel type, in order that the forward part of the chair may not be too high to slide or roll under a table and seat the occupant close to the same.

An additional object of the invention is to provide the basic chair with independently mounted and collapsible arm rest and back members, designed to reduce the folded chair to a size to fit, when the back is folded down, into a large suitcase or the luggage compartment of an automobile.

Another object of the invention is to build the chair with a unitary set of upright frames which are rigid and form a permanent support for a chair seat or for a top or superstructure in case the frames are used for a table, sectional scaffold or other skeleton-type supporting structure.

An important object of the invention is to construct the chair of few and simple parts and for easy handling and adjustment.

With the above objects in view and any others which may suggest themselves from the description to follow, a better understanding of the invention may be had by reference to the accompanying drawings, in which—

Fig. 1 is a side elevation of a wheel chair incorporating the features of the invention, a fabric seat element and the front wheel on the

2

near side being omitted for the sake of clarity; Fig. 2 is a front elevation;

Fig. 3 is a top plan view of a detail, taken on the line 3—3 of Fig. 2;

Fig. 4 is a front elevation of the chair not quite fully gathered or collapsed;

Fig. 5 is a top plan view of the chair;

Fig. 6 is a duplication of the diagonal brace showing of Fig. 2, on an enlarged scale and in complete form, representing the maximum width of the chair;

Fig. 7 is a top plan view of the showing in Fig. 6;

Fig. 8 is a section on the line 8—8 of Fig. 7, on a still larger scale;

Fig. 9 is a duplication of the bottom portion of Fig. 8 on a highly magnified scale;

Fig. 10 is a view similar to Fig. 6, showing the diagonal braces partly folded to represent a reduced width of the chair;

Fig. 11 is a view similar to Fig. 10, showing the diagonal braces completely folded in the representation of the fully gathered or collapsed form of the chair;

Fig. 12 is an enlarged section of one diagonal brace, taken on the line 12—12 of Fig. 6;

Fig. 13 is an enlarged section of a seat attaching device, taken on the line 13—13 of Fig. 5;

Fig. 14 is a front elevation showing the invention applied to a camp chair or stool;

Fig. 15 is a side view of the showing in Fig. 14;

Fig. 16 is a view similar to Fig. 14, showing the chair collapsed; and

Fig. 17 is another view similar to Fig. 14, showing a modification.

Referring specifically to the drawings, it is apparent that the body of the chair includes a pair of identical, laterally-spaced side frames of substantially square form and tubular construction, the frames having frontal uprights 15, rear uprights 16, top rails 17 and bottom rails 18. To form a wheel chair the frames are extended from the rear with caster brackets 19 for the small rear wheels 20; and the frontal uprights 15 are also extended rearwardly with brackets 21 carrying outwardly projected shafts 22 to receive the large front wheels 23. The frame assembly is set between the wheels with a slight rearward tilt, as is the customary practice.

The frontal uprights 15 are open at the top; and the rear uprights carry rigidly attached tubes 24 formed with forwardly extended sockets 24a to receive the rear ends of the top rails 17. The tubes 24 are open at the top and bottom. The top rails 17 are at seat level; and above them

is a pair of tubular rails 25 designed to serve as arm rests. The rails 25 have downward terminal legs 26 which enter the front uprights 15 and the tubes 24 of the chair frames as shown in Fig. 1, full lines indicating the collapsed position of the rails 25. However, these may be raised to any position, such as either of the dotted line positions shown, to serve as arm rests. A spring-pin latch 27 carried by each of the frontal uprights 15 and the tubes 24 is applicable to properly-located holes or depressions in the frontal arm rest legs 26 to station the arm rests 25 in the raised and collapsed positions; or any other suitable means may be employed for the adjustment of the arm rests.

Primarily, the chair is designed to be gathered or collapsed from a position where its side frames have a maximum spacing—such as 18 inches—to a point where they meet, as indicated in Fig. 11. The frames thus become compactly assembled, and the chair is fully collapsed. A fabric back 28 is disposed between the hinged upper portions 16a of the rear uprights 16, such back preferably being formed with a vertical hem 29 at one side and with a series of such hems 29a at the other side, the hem 29 and a selected one of the hems 29a according to the spacing of the side frames—provided uprights 16 being slidably mounted on the same. A similarly mounted fabric seat 30 is shown only in Figs. 2, 5 and 13 is disposed between the top rails 17, and it will be understood that the back 28 and seat 30 will fold between the frames when these are collapsed, Fig. 4 showing the folding action of the back 28. The seat 30 is deleted in Fig. 4 for the sake of clarity.

Referring to Fig. 13, each side of the seat 30 of Figs. 2 and 5 is removably secured to the top rail 17 of the adjacent side frame by means of a bar 30b received in a seat hem 30a. Screws 30x are employed to fasten bar 30b and an intermediate rail-seating saddle 30c to rail 17. The side of the seat 30 which is shown in Fig. 13 has a number of hems 30a as is also indicated in Fig. 5, and the related bar 30b will be located in the proper seat hem 30a for the selected spacement of the side frames as will be presently explained.

The frames are connected across by a pair of diagonal braces. While crossed diagonal braces are not basically novel in a folding chair, those employed by us have been improved with novel features to adapt them to the chair frames described above and render the chair adjustable to several widths. As mentioned in an early section, conventional folding chairs are commonly used or handled only in the fully open or collapsed positions, not being constituted to be set at or adjustable to intermediate positions. However, we have found it of advantage to set the chair at different widths, wherefore only one size of chair need be manufactured, as the same chair is usable for persons of different ages or sizes by being set to the desired width. Also, the chair can be contracted to less than its ordinary width for facility in rolling it through a narrow theatre or railroad car aisle to the place where the occupant is seated, to receive him and enable him to be wheeled out without appreciable discomfort.

It is noted that the top and bottom rails 17 and 18 of the side frames are fixedly spaced and cannot be connected by diagonal braces whose upper ends fall as the braces open, and rise as the braces close. In our novel embodiment the height of the braces 31, 32 is the same at all points in their folding and unfolding movements, enabling the ends of the braces 31, 32 to be connected be-

tween the fixedly spaced top and bottom rails 17 and 18 of the side frames. The constant height of the diagonal braces 31, 32 is made possible by constructing each of them in two major parts, these being a lower tube 31 and an upper tube 32 partly telescoped in the lower one. The tube 31 has its lower end secured to a sleeve 33 rotatably mounted on the bottom rail 18 of one of the chair frames, while the tube 32 has its upper end secured to a sleeve 34 rotatably mounted on the top rail 17 of the other chair frame. The other diagonal brace is similarly mounted in relation to the other rails 17 and 18, so that the braces are in longitudinal alinement when the frames are fully gathered—as shown in Fig. 11—and open in crossed relation when the frames are separated, as shown in Fig. 2. It is now apparent that the lengths of the tube assemblies 31—32 will change by telescopic action in adaptation to the gathered and spread positions of the chair frames.

In order to coordinate the action of the diagonal braces 31, 32 so that their effect on the side chair frames may be uniform or balanced, the braces are primarily set close from front to rear—as seen in Fig. 1—and connected in a manner to make the chair frames adjustable to two or more widths between the maximum one and the fully collapsed form, as well as to coordinate the positions and movements of the frames at all times.

The connections between the diagonal braces 31, 32 actually extend only from the lower tubes 31 thereof. Thus, each of these has a longitudinal series of studs 35—four are shown—extending inwardly and identically spaced. The studs are tubular to make them lighter, but may be of solid construction if desired. With the pair of diagonal braces 31, 32 closely set—as in Fig. 1—it is possible to align the top stud 35 of one brace with that of the other brace; and a sleeve 36 is positioned to receive and span the aligned studs 35, locking them against relative lateral movement, as shown in Fig. 8.

The locations of the studs 35 are determined by the desired spacing of the chair frames. Thus, the maximum spacing thereof positions the diagonal braces 31, 32 as in Fig. 6. The uppermost studs 35 are therefore positioned where the tubes 31 cross; and the crossing point of the tubes 31 is necessarily at mid-height because of the parallelism and fixed height of the frames. Now, when the chair frames are gathered to a certain extent, the condition just specified must still obtain, which requires the pivot to be assumed by a second pair of matching studs 35 set lower on the tubes 31. A third set of studs 35 serves for the next adjustment; and Fig. 10 shows the final adjustment with the chair in the narrowest position of use and that a fourth or lowermost set of matching studs 35 serves in such event.

It is now apparent that the studs 35 may be paired according to the desired chair width, and the intersection of the lower brace tubes 31 fixed by the application of the retaining sleeve 36. However, the set width of the chair frames cannot be fixed or relied upon as long as the upper tubes 32 are freely slidable in the lower ones. In other words, it is still possible, after the tubes 31 have been pivotally anchored, for the chair frames to be gathered by imparting telescoping or retracting movement to the tubes 32. It is thus necessary to lock these tubes 32 against sliding movement in the tubes 31 every time the width of the chair has been tentatively set by means of the matching studs 35. We have found

by experiment, incidentally, that the locking of only one tube 32 is sufficient to fix the chair at a chosen width; and means for accomplishing this are carried by the frontal tube 31, with a control readily accessible from the outer or frontal side thereof.

The means just referred to consist in part of an aperture 40 made in the frontal wall of the tube 32, and a longitudinal series of openings 41 made in the frontal wall of the tube 31, as shown in Fig. 12. The positions of these openings are governed by the predetermined width settings of the chair frames. Thus, when the frames are parallel and at maximum width the first or uppermost opening 41 is made to register with the aperture 40, as shown in the same figure. Now, when the chair is adjusted to the next lesser width, the second opening 41 will be located to register with the aperture 40, and so on for the still lesser widths of the chair—as indicated in Fig. 10. Of course, the maximum folding of the frames places the diagonal braces 31, 32 abreast—as in Fig. 11—and does not make use of the aperture 40 or openings 41.

A conventional type of spring pin 45—clearly shown in Fig. 9—is employed to lock the tubes 32 and 31 at any longitudinal adjustment of use made in the manner just described. A single spring pin is made to suffice for all the adjustments by making the spring pin 45 assembly movable to any of the openings 41. For this purpose the front wall of the tube 31 is reinforced by an outer plate 46 made with tapped bores 47 opposite the openings 41. The spring pin 45 is carried by a housing 48 formed with a threaded nipple 49. Fig. 12 shows that the housing 48 has been screwed with its nipple 49 into the first or uppermost bore 47, and that the spring pin projects into the aperture 40 of the tube 32. Thus, when telescoping the tube 32 into the tube 31, the pin 45 is retracted slightly to clear the end of the tube 32 and allowed to snap into the aperture 40 when the latter comes in line with the pin. Likewise, when the chair is to be set for the next lesser width, the pin housing 48 is unscrewed and applied to the next tapped bore 47. Now, when the tube 32 is telescoped further, it locks automatically, as before. Consequently, the spring pin 45 need only be withdrawn slightly—by means of a finger knob 50 easily reached from the front—when the chair is again to be widened or the diagonal braces 31, 32 taken apart. The braces 31, 32 can be readily taken apart after the seat 30 and the seat back 28 have been removed from one side frame by simply spreading the side frames to pull the brace members 32 out of the sleeves 31. Disconnection of the braces 31, 32 affords a convenient means for re-locating the pivot sleeve 36 when the widths of the seat 30 and back 28 are to be changed as would be the case when a major change in the width of the chair frame spacing is to be affected. This will be explained later on.

The terminal sleeves 33 and 34 of the tubes 31 and 32 are of course slidable on the frame rails 17 and 18 in order to enable the diagonal braces to be properly located and separable sufficiently to permit the insertion or removal of the intermediate sleeve 36 when a change of the matching studs 35 is made without changing the width of seat 30 and its back 28. The rails carry limiting collars 51 in relation to the sleeves 33 and 34; and the collars have removable pins 52 to permit the separation of the collars from the said sleeves when the diagonal braces are to be separated. It

will be apparent that the collars 51 acting through the braces 31, 32 serve to maintain the front and rear members 15, 16 of the side frames in alignment when the sections 31, 32 of the respective braces are telescopically connected. In this connection it is to be noted that when the seat 30 and back 28 have been disconnected from one side frame to conform to a new spacing of the side frames it is not necessary to move any of the collars 51 in order to properly relocate the pivot sleeve 36 of Figs. 1 and 7 for the new spacing of the side frames. This naturally follows from the fact that when the seat 30 and back 28 are disconnected at one side, the side frames can be swung outwardly to pull brace sections 32 entirely out of brace sections 31 and admit of the necessary bodily lateral movement of the side frames for relocation of pivot sleeve 36 on the proper pair of studs 35. It is then a simple matter to re-telescope the brace sections 32 into their companion sleeves 31 and re-connect the free side of the seat 30 and back 28 to the related side frame. By leaving collars 51 fixed no trial and error adjustment of same is necessary to achieve alignment of the ends 15, 16 of the side frames (see Fig. 1) after a side frame spacement change has been made.

The bottom rails 18 are extended forward as shown in Fig. 1 to serve as supports for a pair of foot-rests 51a. These are pivotally mounted on the rails to be foldable from the positions of use shown in Figs. 2 and 5 to those indicated in Fig. 4. Suitable stops may be provided to limit the swing of the foot-rests to the extreme positions indicated, and it is not believed necessary to illustrate any particular type of stop.

It will be evident from the above description that we have provided a chair which is not only foldable from the open to the closed position but adjustable by positive means to a suitable number of widths. Therefore, the chair need not be made in different sizes or widths, since one size of chair is adjustable to persons of different sizes. This feature not only makes for economy in manufacture, but eliminates the keeping of certain chairs idle while others are in use. Further, in the case of a child the chair is of proper initial width when purchased, and can be kept in use as the occupant grows by the mere adjustment to greater width. Also, as mentioned before, the adjustability of the chair is of benefit to the person using it when passage through a narrow aisle or space is desired. Further, the adjusting mechanism is compactly assembled below the chair seat, taking up little room and presenting a handy control. Further, the telescopic diagonal braces 31, 32 are confined between the fixed top and bottom rails 17, 18 of the chair frames, leaving the space above the latter to be used as desired, such as for the application of the independent arm rests 25. Thus, in the case of a wheel chair the arm rests may be in use at any desired height or dropped to the bottom positions to enable the forward portion of the chair to roll under a table, all without prejudice to or interference by the chair adjusting mechanism. Further, the latter only serves to connect and space the chair frames and at no time bears any of the weight imposed on the chair, as is the case in camp chairs or other structures formed with diagonal braces or legs. In the improved chair, only the upright frames bear the weight of the occupant or other superimposed object, relieving the diagonal braces 31, 32 of strain and enabling them to be made of light material. Further, each

adjustment of the frontal lower tube 31 with its upper tube 32 creates a fixed triangle between the bottom rails 18 of the chair frames, the locked diagonal brace 31, 32 and the chair frame rail 17 connecting with the top of such brace 31, 32; and such triangle maintains the chair frames properly adjusted without necessitating an additional control for the companion tube 32. Finally, it is apparent that the simple nature of the adjusting mechanism plus the tubular construction usable for most of the parts making up the chair render the same light, strong and easy to handle.

Figs. 14 to 16 show the application of the invention to a camp chair or stool. In such a case a single pivoting assembly 55 is employed between the sleeve members 55a of the diagonal slidably telescoping braces 55a, 55b, since the chair is used only at full width. A sectional seat 56 is secured by clips 57 to the top rails of the U-shaped side frames 56a, 56b and serves to maintain the spacing of these, particularly when the seat is occupied. In addition, the sections of the seat 56 are pivoted at 58 midway between the side frames and therefore foldable as indicated in Fig. 16 when the frames are gathered to collapse the chair.

Fig. 17 shows a modification of the structure of Fig. 14 when it is used as a support for a table top or scaffold. Such a top or scaffold 59 is shown deposited on the frame structure. In this case a simple link 60 pivoted at 61 to one leg of one of the side frames 63 hooks on a pin 62 carried by the corresponding leg of the other side frame 63, fixing the spacing of the side frames 63. The Fig. 17 structure has a single pivoting assembly 55 and telescoping braces corresponding to those indicated 55a, 55b of Figs. 14, 15 and 16.

The structures of Figs. 14 and 17 serve to further illustrate the fact that whatever part or assembly is mounted on the frame structure, it is fully supported by the upright side frames thereof, relieving the interconnecting diagonal braces of strain, pressure or service as supports.

While we have described the invention along specific lines, various minor changes or further refinements, such as the substitution of sliding overlapping bars for the telescoping tubes, may be made therein without departing from its principle, and we desire to consider all such changes and refinements as coming within the scope and spirit of the appended claims.

We claim:

1. A structure having a pair of upstanding side frames, a pair of crossed diagonal braces extending transversely between the frames and with ends pivotally secured to the latter, each brace composed of a pair of sections adjustable longitudinally relative to each other, and means to fix the sections of each brace at given points of adjustment comprising an aperture in one section, a series of openings in the other section spaced according to said points and selectively registerable with said aperture by the corresponding adjustment of the sections, a stop pin movable by way of the registering opening to enter the aperture and fix the sections against relative movement, a carrier for the stop pin, and means to attach the carrier to the other section adjacent to any of said openings with said stop pin in operative position relative to the same.

2. The structure of claim 1, said means comprising tapped recesses in said other section forming entrances to said openings, and a nipple extended from said carrier and adapted to thread

into the recess of the opening to which the carrier is applied.

3. A structure having a pair of upstanding side frames, a pair of crossed diagonal braces extending transversely between the frames and with ends pivotally secured to the latter, each brace composed of a pair of sections adjustable longitudinally relative to each other, series of longitudinally spaced cooperative elements carried by similarly positioned ones of said sections to connect them pivotally to each other, said elements being adapted to register in pairs at the crossing point of the braces according to changes in the spacing of the frames, and means to fix the sections of each brace at given points of adjustment comprising an aperture in one section, a series of openings in the other section spaced according to said points and selectively registerable with said aperture by the corresponding adjustment of the sections, a stop pin movable by way of the registering opening to enter the aperture and fix the sections against relative movement, a carrier for the stop pin, and means to attach the carrier to the other section adjacent to any of said openings with said stop pin in operative position relative to the same.

4. A structure having a pair of upstanding side frames including horizontal elements in the top and bottom regions, and a pair of crossed and longitudinally adjustable diagonal braces extending transversely between the frames and with ends pivotally and slidably secured on said elements, whereby to enable the frames to be fully gathered as the braces fold to positions abreast of each other, removable pivot means connecting corresponding portions of said braces and disposed between the same, said pivot means being accessible when the braces are laterally separated.

5. A structure of the class described, having a pair of upstanding side frames, a pair of crossed and longitudinally adjustable diagonal braces extending transversely between the frames, means pivotally securing the ends of the braces to said frames, a series of longitudinally spaced studs carried by each of the braces, said series of studs being disposed in opposition to each other, different studs of each series being adapted to register as a pair at the crossing point of the braces according to changes in the spacing of the frames, collar means receiving registering ones of said studs for pivotally connecting said braces, and said pivot means disposing the braces adjustably along said frames in directions to gather and separate matching studs of said series for the application of said sleeve.

6. The combination set forth in claim 5, and said pivot means comprising sleeves on the ends of said braces, and horizontal bars provided by said frames on which said sleeves are slidably mounted.

7. A structure of the class described having a pair of upstanding side frames, a pair of crossed diagonal braces extending transversely between the frames, means pivotally securing the ends of the braces to said frames for relative lateral sliding movement, whereby said braces may be moved bodily toward and away from one another, each brace comprising a pair of sections adjustable longitudinally relative to each other, corresponding sections of each brace having a series of longitudinally spaced pivot element receiving means, a pivot element positionable to connect opposed ones of said pivot element-receiving means for 75 pivotally connecting said braces together, corre-

sponding ones of said pivot element receiving means registering at the crossing point of the braces according to changes in the lateral spacing of the frames, and means for preventing lateral sliding of said braces on said frames and with respect to one another.

8. A structure of the class described having a pair of upstanding side frames, crossed extensible braces pivotally connecting said side frames, pivot means wholly interposed between corresponding portions of said braces for pivotally connecting the same, said pivot means comprising a lineally spaced series of pivot receivers on each of said aforementioned brace portions, and a connector selectively engageable with opposed ones of said receivers which are brought into registry with one another at different spacements of said side frames.

9. The combination set forth in claim 8 and the pivotal connection between at least one of said braces and said frames admitting for at least limited bodily lateral movement of said brace whereby to provide access to said connector for release of same.

10. The combination set forth in claim 8 and said connector being a floating one and retained in place by proximity of said braces, and the pivot connection between at least one of said braces and said frames admitting of limited lateral bodily sliding movement of said brace whereby to provide access to said connector for removal of same.

11. The combination set forth in claim 8 and said connector being a floating one and retained in place by proximity of said braces, and the pivot connection between at least one of said braces and said frames admitting of limited lateral bodily sliding movement of said brace whereby to provide access to said connector for removal of same, and means carried by one of said particularly mentioned braces and the frame for retaining said brace against lateral movement.

12. A structure having a pair of upstanding side frames having fixedly spaced upper and lower portions, a pair of crossed diagonal braces extending transversely between the frames and with ends pivotally secured to said frame portions, each brace composed of a pair of sections adjustable longitudinally relative to each other, series of longitudinally spaced pivot-providing elements carried by similarly positioned ones of said sections to connect them pivotally to each other, said elements being adapted to cooperatively register in pairs at the crossing point of the braces according to changes in the spacing of the frames, means to fix the sections of each brace at given points of adjustment and cooperating with the operatively functioning pair of pivot-providing elements to hold the side frames in an adjusted relationship, said means including an aperture in one section of one brace only, a series of openings in the other section of said particularly mentioned brace and spaced according to said points and selectively registerable with said aperture by the corresponding adjustment of the sections of said particularly mentioned brace, and a stop pin movable by way of the registering opening to enter the aperture and fix the sections against relative movement.

13. A structure of the class described comprising a pair of upstanding side frames having fixedly spaced upper and lower portions, adjacent crossed and extensible braces pivotally connecting said side frames and connected to different ones of said fixed upper and lower frame portions,

each brace comprising separable slidably connected sections, selectively cooperable pivot-providing means for connecting said braces and arranged in series longitudinally of opposed sides of corresponding sections of said braces, whereby to be disposed between the latter, individual ones of said pivot-providing means of each series being brought into cooperation with one another at different spacements of said side frames, means cooperating with the operatively functioning ones of said pivot-providing means to hold said side frames in fixed spacement and comprising relative movement-preventing means operatively associated with the sections of one brace only, and means retaining at least one section of one of said braces against shifting movement axially of said pivot-providing frame portions, whereby to maintain said side frames in alignment when the brace sections are connected.

14. A structure of the class described comprising a pair of upstanding side frames having fixedly spaced upper and lower portions, adjacent crossed and extensible braces pivotally connecting said side frames and connected to different ones of said fixed upper and lower frame portions, each brace comprising separable slidably connected sections, selectively cooperable pivot-providing means for connecting said braces and arranged in series longitudinally of opposed sides of corresponding sections of said braces whereby to be disposed between the latter, individual ones of said pivot-providing means of each series being brought into cooperation with one another at different spacements of said side frames, and means retaining at least one section of one of said braces against shifting movement axially of said pivot-providing frame portions whereby to maintain said side frames in alignment when the brace sections are connected.

15. A structure of the class described comprising a pair of upstanding side frames having fixedly spaced upper and lower portions, adjacent crossed and extensible braces pivotally connecting said side frames and connected to different ones of said fixed upper and lower frame portions, each brace comprising separable slidably connected sections, selectively cooperable pivot-providing means for connecting said braces and arranged in series longitudinally of opposed sides of corresponding sections of said braces, whereby to be disposed between the latter, individual ones of said pivot-providing means of each series being brought into cooperation with one another at different spacements of said side frames, and means cooperating with the operatively functioning ones of said pivot-providing means to hold said side frames in fixed spacement and comprising relative movement-preventing means operatively associated with the sections of one brace only.

16. A structure of the class described comprising a pair of upstanding side frames having fixedly spaced upper and lower portions, crossed braces between said frames, said brace including extensibly connected sections, means including said fixedly spaced frame portions for pivotally connecting outer ends of said brace sections to said side frames, pivot means associated with corresponding ones of said brace sections and operable to pivotally connect the same at longitudinally spaced points, and means independent of said pivot means and carried by one brace only for locking the sections thereof against relative movement, and said independent means cooperating with said pivot means and fixedly

11

spaced frame portions to retain said side frames in predetermined spacement and the sections of the other brace against relative movement.

17. The combination set forth in claim 16 and means mounting at least one of said braces for bodily shifting movement toward and away from the other brace to facilitate connection and disconnection of same, and means carried by at least one of the related fixedly spaced frame portions for preventing such movement whereby through said braces to retain said side frames in alignment.

18. A structure of the class described having a pair of upstanding side frames including horizontal elements in the top and bottom regions, a pair of crossed diagonal braces extending transversely between the frames, each brace comprising separable longitudinally adjustable sections, means pivotally securing the outer brace ends on said frame elements, removable pivot means connecting corresponding sections of said braces and disposed between the same whereby to admit of said side frames being brought into contiguous engagement with one another while said pivot remains in place, at least one of said braces being laterally slidable on the related horizontal frame elements, whereby to afford access to said pivot means when the braces are separated laterally from one another.

19. A structure of the class described comprising a pair of upstanding side frames having fixedly spaced upper and lower portions, adjacent crossed and extensible braces pivotally connecting said side frames and connected to different ones of said fixed upper and lower frame portions, stop means on said upper and lower frame portions and engaging said pivoted brace ends to prevent longitudinal shifting of the braces thereon, each brace comprising separable slidably connected sections, selectively cooperable pivot-providing means for connecting said braces and arranged in series longitudinally of opposed sides of corresponding sections of said braces, whereby to be disposed between the latter, individual ones of said pivot-providing means of each series being brought into cooperation with one another at different spacements of said side frames, and said side frames being bodily shiftable upon disconnection of said brace sections to admit of pivot connection change between said particularly mentioned brace sections without shifting of said stop means.

20. The combination set forth in claim 19, and means cooperating with the operatively functioning ones of said pivot-providing means to hold said side frames in fixed spacement and comprising relative movement-preventing means operatively associated with the sections of one brace only.

12

21. A structure comprising a pair of upstanding side frames, a pair of crossed and longitudinally adjustable diagonal braces extending transversely between the frames and with ends pivoted to the latter, and a free swinging movement-permitting pivot means connecting the braces at their crossing point to facilitate the coordinated gathering and separation of the side frames and to admit of contiguous engagement of said side frames while said pivot is in place.

22. A folding variable width seat or the like comprising a pair of upstanding side frames, a pair of crossed adjacent diagonal braces extending transversely between the side frames and with ends pivoted to the latter, means preventing axial movement of the pivoted ends of said braces on said frames, each brace comprising separable longitudinally adjustable sections, one section of each brace providing a longitudinally extending guideway open at its inner end and receiving at least a portion of the companion section, brace-connecting pivot means interposed between the same and selectively connecting corresponding sections at longitudinally spaced points, said pivot means retained in place by the proximity of said braces, and said frames being bodily movable upon separation of said brace sections to admit of relocation of said pivot means.

23. The combination set forth in claim 16, the sections of at least one of said braces being separable and the section thereof having brace connection pivoting means associated therewith being shiftable axially of the related one of the fixedly spaced side frame portions whereby brace sections which have the brace connecting pivot means can be laterally separated to facilitate engagement and disengagement of said brace section connecting pivot means.
